F. A. COOK.
TYPE WRITING MACHINE.
APPLICATION FILED JULY 17, 1915.

1,194,362.

Patented Aug. 15, 1916.

UNITED STATES PATENT OFFICE.

FRANK A. COOK, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,194,362.

Specification of Letters Patent. Patented Aug. 15, 1916.

Application filed July 17, 1915. Serial No. 40,364.

To all whom it may concern:

Be it known that I, FRANK A. COOK, a citizen of the United States, residing in Hartford, in the county of Hartford and 5 State of Connecticut, have invented certain new and useful Improvements in Type-Writing Machines, of which the following is a specification.

This invention relates principally to type-writing machines for writing upon a number of superposed webs or continuous sheets, especially those which are intended to be torn off in sections from the body of the web, as, for example, when the webs comprise 10 a series of printed forms, each adapted to be removed when the typewriting thereon is completed. In such work it is desirable to employ ink ribbons or carbon sheets interleaved with the webs for making 15 the duplicate copies.

A machine for performing work of this character is shown and described in United States Letters Patent No. 1,132,055, to Lester A. Wernery and Jesse A. B. Smith, dated 20 March 16, 1915.

In the machine shown in the above-mentioned Letters Patent, the platen, together with a paper-shelf, is shiftable on the carriage from a normal or writing position, in 25 which the paper is held against the platen by the feed rollers, to a position in which the platen is removed from the feed rollers to relieve the pressure of the latter on the paper. In that machine, in order to relieve 30 the friction on the web due to the wrapping of the same around the platen, the platen, when shifted to release the paper, is moved in conjunction with the paper shelf, to a position such as to provide a clear and relatively 35 straight path for the web; and along this path the web and the carbon sheets receive their adjustments incident to the removal of written lengths from the web and to the positioning of the web for further 40 writing. The platen is locked against accidental displacement from its normal or writing position; and, formerly, means independent of the platen-shifting mechanism have been employed to effect such locking of 45 the platen.

The present invention has as an object thereof, the provision of a device for unlocking the platen preliminary to shifting the same, which device forms part of the

shifting mechanism, so that upon operation 55 of the latter the platen is in effect automatically unlocked. By this means the number of parts is reduced; and a distinct unlocking operation is eliminated to great advantage, in that both operations may be 60 done substantially simultaneously with one hand, the operator's other hand being free to attend to the web and carbon sheets.

A further feature of the present invention relates to the gage for determining the 65 length of the printed sheets to be removed from the web. Heretofore this gage has been unyieldingly attached to the papershelf, with the result that in using the same to return the parts to normal position it has often 70 been bent or distorted. Furthermore, such attachment did not allow the gage to be collapsed toward the machine for compactness when not in use or in packing.

In a form of the invention presently to 75 be described in detail, the gage is pivoted to the platen frame and is held yieldingly in normal position on the latter by a spring. Forward movement of the gage causes it first to release a latch which locks the platen 80 frame in normal position, and then to engage and throw the frame to paper-releasing position. The spring permits backward movement of the gage independently of the frame, so that it may be collapsed toward 85 the machine, and so that it cannot be bent by being used as a means for returning the platen frame to normal position. The gage itself, therefore, in a single forward movement, may have the double function of unlocking and throwing the platen frame. The gage may, however, be used only as a 90 gage, and another bar or handle, similarly attached, may be used to unlock and move the platen frame. 95

Other features and advantages will hereinafter appear.

In the accompanying drawings, Figure 1 is a view in perspective, showing the platen and assembled mechanism of the present invention in printing position on the platen carriage. Fig. 2 is a fragmentary view in rear elevation of the parts shown in Fig. 1. Fig. 3 is a fragmentary view in side elevation, showing the parts in normal or printing position, except that the gage is collapsed as for packing. Fig. 4 is a view in side elevation, showing the parts in nor-

mal or printing position. Fig. 5 is a view similar to that of Fig. 4, except that the platen is shown as unlocked and commencing its movement to paper-releasing position.

Referring to the drawings, the platen 7, fixed to a shaft 8, has bearing on a frame comprising a pair of plates 9, which directly support the platen. The plates 9 are fixed 10 to a rock shaft 10 journaled in the end members 11 of the carriage, so that at certain times the platen may be swung bodily about the shaft 10 as an axis. A channel bar 33 ties together the plates 9 to give strength to 15 the swinging frame. This frame, with the platen revolvably mounted therein, is, during the printing operation, locked in the position shown in Fig. 1. For locking the frame, a rock shaft 12 carried by the plates 20 9, has affixed to it a pair of hooks 13 adapted to engage one of the carriage tie rods 14. The ends of the plates 9 are turned at 15, and have seats 16, whereby the swinging frame may be supported on the rods 14. 25 Coil springs 17, each fast at one end to the adjacent hook 13 and at the other end bearing on the channel bar 33, tend to rock the shaft 12 to throw the hooks 13 into engagement with the rods 14 and to maintain such 30 engagement.

The platen, when in printing position, has a line-space movement, preferably effected from the usual hand wheel 18 or from the ratchet wheel 19, the latter receiving a pre- 35 determined throw from a pawl 20 on a slide 21 actuated by a finger key lever 22 common to Underwood typewriting machines. The shaft 23 to which the hand wheel 18 and ratchet wheel 19 are fixed, is mounted to rotate in the usual way on the carriage end-pieces 11. It is connected to the platen shaft by means of gears 24, 25 and 26. The gear 24 is fast to the shaft 23, and the gear 25, which is of the same size and has the 40 same number of teeth, is fast to the platen shaft 8, face to face with the gear 24. The gear 26 is a pinion loosely carried on the shaft 10, which serves as the axis of the swinging platen-supporting frame. The 45 face of the pinion 26 is of a width to cause it to engage simultaneously with the teeth of the gears 24 and 25. Any movement of the hand wheel 18 or line-space mechanism is, therefore, transmitted to the platen. 50 When the platen is swung by its frame in the paper-releasing and inserting operation, the gear 26, being on the axis 10, remains in mesh with both the gears 24 and 25.

In the Patent No. 1,132,055 to Wernery 55 and Smith, above referred to, it is stated that in the operation of removing a printed length from the web, and in readjusting the web for printing the next length, the platen is swung from printing position to a position away from the feed rolls, so that the

web no longer wraps around the platen, but may be moved freely in substantially a straight line from back to front of the machine. While the platen is in this position, the carbon sheets between the plies or folds 76 of the section of the web to be removed, are drawn back into the length or section of web next to be printed, and after removal of a length of the web and re-positioning of the web, the platen is returned to its normal position against the feed rolls. The forward or paper-releasing throw of the platen frame is finally arrested by any suitable means, as by a stop or screw 47 on the shaft 10 engaging the plate 46 on the frame. The 80 paper and carbon sheets are fed to the platen over a table 30^a, having side rails 30. A bar 31 ties together the table rails 30. Over this bar the web is passed and is then turned down under the platen and up and 85 out at the top, onto a supporting and guiding shelf 32, which latter, in its normal or printing position, is inclined upward and rearward from a point near the platen. The shelf 32 is secured to and supported by 90 the channel bar 33 which ties the plates 9 of the swinging frame. The bar 34, which is the gage, has a shoulder or offset 35, and has ears 36 by means of which it is loosely mounted on the rock shaft 12 which carries 95 the platen-locking hooks 13. Collars 37 and 38 fast to the shaft 12, prevent longitudinal displacement of the bar 34. The collar 37 carries a lug 39 against which the bar 34 is normally held by a coil spring 40 on 100 the shaft 12, one end of the spring bearing against the bar 34 and the other end being attached to the collar 37. The bar is normally set at the same angle as the shelf 32, and as it connects to the shaft 12, near the 105 crimped upper edge 41 of the shelf, it may be considered as an extension of the shelf. Upon feeding or drawing the leading edge 110 of the web up to the offset 35 at the end of the bar, the latter acts as a gage to determine the length of the paper to be removed on each cutting of the web. That the gage may be adjustable as to length, the bar 34 is preferably in two sections united by a thumb screw 42 on a stud fast to one section 115 and adjustable along a slot 43 in the other section.

The bar 34 may be used as a handle by which to shift the platen from normal to paper-releasing position, although a separate handle 44 fast to the shaft 12 may also serve the purpose. To so shift the platen it is merely necessary to seize and draw forward the bar 34. Assuming the parts to be in normal (Fig. 4) position, a draw on the 125 bar against the action of the spring 17, causes the bar, by reason of its engagement with the lug 39 on the shaft 12, to rock that shaft, thus moving the hooks 13 to Fig. 5 position in which the platen is unlocked 130

from the bar 14. To permit this movement of the bar without movement of the frame as a whole, the shelf 32 is cut away at 45. Continued movement of the bar causes the 5 bar to strike the shelf 32, and thereafter to swing the frame and all parts carried by it, to a position (shown and described in the patent hereinbefore referred to), in which the shelf 32 and the bar extend horizontally 10 forward of the platen in substantial continuation of the table 30^a, with the platen well elevated above the feed rolls. The handle 44 being attached to the rock shaft 12, acts in the same way as the gage bar, to unlock and shift the platen; the shelf 32 being cut away at 44^a to permit of the preliminary unlocking operation, before the handle 15 engages and moves the shelf and frame to paper-releasing position. When the parts 20 are in this last position, the web is drawn to the offset 35 on the gage, and held while the carbons are drawn back by the means shown in the patent mentioned. The printed section is then cut off by turning the same 25 against a blade 46 carried by the frame plates 9; and the new section of the web, with the carbons interleaved therein, having been positioned, the frame is swung back to normal, (Fig. 4) position. When, on the 30 return of the frame, the hooks 13 strike the bar 14, they are cammed over the latter by cam surfaces 48 at the ends of the hooks, and the springs 17, to effect automatic locking.

25 The return movement of the parts may be effected by the handle 44, or the frame may be seized at any convenient part thereof and swung back. The gage bar 34 is not intended to be used to return the frame to normal 40 position, because, being preferably of relatively light material, it might be bent or distorted by undue pressure on it after the frame has been stopped by the bar 14. Owing to the manner in which the gage bar is 45 mounted on the rock shaft 12, it may be folded or rocked backward against the action of its spring 40, (as shown in Fig. 3), independently of the frame. This freedom of backward movement has the further advantage of permitting the bar to be collapsed and held down for compactness in 50 packing the machine.

It will be noted from the foregoing that the unlocking of the platen in the paper-releasing operation is, in effect, automatic, 55 because it requires no action other than that of throwing forward the platen and shelf-carrying frame.

Variations may be resorted to within the 60 scope of the invention, and portions of the improvements may be used without others.

Having thus described my invention, I claim:

1. In a typewriting machine, a carriage, a 65 frame on said carriage having a bodily

swinging movement in a direction at right angles to the direction of letter-feed movement of the carriage, a platen revolvably mounted in said frame to swing therewith, means for locking the frame against such 70 movement on the carriage, and means for unlocking and, in a single operation, swinging the frame to throw the platen to a paper-releasing position on the carriage.

2. In a typewriting machine, a carriage, 75 a frame on said carriage having a bodily swinging movement in a direction at right angles to the direction of letter-feed movement of the carriage, a platen revolvably mounted in said frame to swing therewith, a 80 latch on said frame for locking the frame in a normal writing position on the carriage, and means for unlatching and swinging the frame with the platen to a paper-releasing position on the carriage. 85

3. In a typewriting machine, a carriage, a platen, a frame on the carriage having the platen revolvably mounted therein, means for swinging said frame with the platen bodily in an arcuate path between a normal writing position and a paper-releasing position 90 on the carriage, means for locking the platen frame in its normal writing position, means for automatically unlocking the frame in the operation of swinging it to paper-releasing 95 position, and means in permanent position on the carriage for effecting line-space movement of the platen.

4. In a typewriting machine, a carriage, a platen, a frame pivoted to the carriage 100 and having the platen revolvably mounted therein, a latch for locking the frame down against the carriage in normal writing position on the latter, and a lever adapted to operate said latch to release the frame and 105 to engage and swing the frame bodily in an arcuate path to a paper-releasing position.

5. In a typewriting machine, a carriage, a platen, a frame pivoted to the carriage 110 and having the platen revolvably mounted therein, a latch for locking the frame down against the carriage in normal writing position on the latter, and a lever pivoted to said frame to have a rocking movement 115 thereon to unlock the frame from the carriage and to serve as a means for throwing the frame bodily in an arcuate path to a paper-releasing position on the carriage.

6. In a typewriting machine, a carriage, 120 a platen, a frame pivoted to the carriage and having the platen revolvably mounted therein, a latch for locking the frame down against the carriage in normal writing position on the latter, and a lever pivoted to 125 said frame to have a limited rocking movement thereon, independently of the frame for unlocking the frame, and thereafter engaging the frame at another point of the lever so that further movement of the lever 130

causes the frame to be swung bodily in an arcuate path with the platen to a paper-releasing position.

7. In a typewriting machine, a platen, 5 means for guiding a web of paper to and around the platen, a gage for measuring the length of written sheets to be cut from the web, means for shifting the platen to release the web therefrom for adjustment of 10 the web after a section of the web has been written and is to be removed, means for locking the platen in normal position against such shift, and means operated by movement of the gage to unlock the platen 15 to permit such shift.

8. In a typewriting machine, a platen, means for guiding a web of paper to and around the platen, a gage for measuring the length of written sheets to be cut from the 20 web, means for shifting the platen to release the web therefrom for adjustment of the web after a section of the web has been written and is to be removed, and means for locking the platen in normal position 25 against such shift, said gage serving as a means for unlocking the platen to permit shift of the same, and as a means for shifting the platen when the same is unlocked.

9. In a typewriting machine, a carriage, 30 a platen, means for guiding a web of paper to and around the platen, a paper shelf inclined upwardly and rearwardly from the platen to receive the paper which has passed around the platen, a gage secured to said 35 shelf to measure lengths of written sheets to be removed from the web, a frame shiftable on the carriage and having the platen and paper shelf secured thereto, so that the shelf may be swung forward and the platen 40 lifted to afford a clear and relatively straight path of movement for the web in the adjusting of the latter when sections thereof are removed, means for locking the platen frame in its normal printing position, and means whereby said gage may be 45 set to unlock the platen frame when sheets are to be removed or positioned.

10. In a typewriting machine, a carriage, a platen, feed rollers for guiding a web of 50 paper around the platen, a gage to measure lengths of written sheets to be removed from the web, a frame in which the platen is revolvably mounted, said frame being shiftable on the carriage to release the web 55 by removing the platen from the feed rollers when lengths of the web are to be removed or positioned, means for locking the platen frame in normal printing position, and means actuated by the gage to unlock 60 the platen frame when desired.

11. The combination with a platen, of 65 means for holding a web of paper against the platen, a frame in which the platen is mounted to be shiftable to and from said holding means so that the pressure on the

paper may be relieved when desired, a gage for measuring lengths of written sheets to be removed from the web, said gage being connected to the frame to serve as a means for shifting the latter when drawn forward, 70 and being yieldingly held in normal position to permit backward movement thereof independently of the frame.

12. The combination with a platen, of 75 means for holding a web of paper against the platen, a frame in which the platen is mounted to be shiftable to and from said holding means so that the pressure on the paper may be relieved when desired, a gage pivoted to the shiftable frame for measuring lengths of written sheets to be removed from the web, a spring for yieldingly holding the gage in normal paper-receiving position on the frame, and a stop on the frame to be engaged by the gage on movement of 80 the latter forward from normal position, whereby the gage may serve as a means for shifting the frame, the gage having backward movement independently of the frame. 85

13. In a typewriting machine, the combination, with a revoluble platen, and means for holding paper against said platen when in normal printing position; of means for locking the platen in said position; a shaft for unlocking the platen when rocked in 90 one direction; a projection fixed to said shaft; and a member for throwing the platen bodily from normal position to release the paper, said member loosely mounted on said shaft and releasably engaged with said projection, so as to automatically rock said shaft and thereby unlock the platen when operated to so throw-said platen. 95

14. In a typewriting machine, the combination, with a revoluble platen, and means for holding paper against said platen when in normal printing position; of means for locking the platen in said position; a shaft for unlocking the platen, when rocked in 100 one direction; a projection fixed to said shaft; and a member for throwing the platen bodily from normal position to release the paper, said member loosely mounted on said shaft and having a normal 105 position in which it is engaged with said projection, so as to automatically rock said shaft and thereby unlock the platen when swung forwardly from such position to so throw said platen, said member arranged 110 to disengage said projection and thereby move independently of said shaft when swung backwardly from its said normal position. 115

15. In a typewriting machine, the combination, with a revoluble platen, and means for holding paper against said platen when in normal printing position; of means for locking the platen in said 120 position; a shaft for unlocking the platen 125

when rocked in one direction; a pair of spaced collars fixed to said shaft, one of said collars having a lug thereon; and a member for throwing the platen bodily from normal position to release the paper, said member being loosely pivoted on said shaft between said collars so as to be held thereby against displacement, and being normally engaged

with said lug so as to automatically rock said shaft and thereby unlock the platen to when operated to so throw said platen.
